UNITED STATES PATENT OFFICE.

AUGUST ARENS AND ERNEST L. TEICH, OF NEW BRITAIN, CONNECTICUT, ASSIGNEES
TO P. & F. CORBIN, OF NEW BRITAIN, CONNECTICUT, A CORPORATION.

LOCK AND NIGHT-LATCH MECHANISM.

980,180.

Specification of Letters Patent.

Patented Jan. 3, 1911.

Application filed August 13, 1910. Serial No. 576,995.

To all whom it may concern:

Be it known that we, AUGUST ARENS and ERNEST L. TEICH, citizens of the United States, residing at New Britain, county of 5 Hartford, State of Connecticut, have invented certain new and useful Improvements in Lock and Night-Latch Mechanisms, of which the following is a full, clear, and exact description.

Our invention relates to locks, and is particularly concerned with improved safety devices for preventing tampering with the so-called night latch mechanism thereof.

Locks of the character to which this invention relates are provided with separate and independent roll-backs for withdrawing the latch bolt operated by the inner and outer knobs respectively. With the outer roll-back a so-called night latch mechanism is employed to prevent rotation of said roll-back by the outer knob when desired. These locks, furthermore, are provided with means for deadlocking the latch bolt when the door is closed to prevent retraction of the bolt by insertion of a suitable implement between the door jamb and the edge of the door. It is also found necessary in locks of this character to prevent unauthorized tampering with the night latch mechanism in a similar manner by insertion of an instrument between the door jamb and the door, and to this end, our invention contemplates mechanism for this purpose comprising means operable by the latch-bolt dead-locking means to dead-lock said night latch mechanism in operative position.

With these objects in view the invention consists in the construction and arrangement of parts, a preferred embodiment of which is illustrated in the accompanying drawings, in which—

Figure 1 is a side view of the lock with the cover plate removed with the parts shown in the position assumed when the door is open and with the night latch mechanism in operative position. Fig. 2 is a sectional view on the line x—x Fig. 1, looking to the left, and with the cover plate and usual cylinder lock mechanism in place. Fig. 3 is a view similar to Fig. 1, showing the parts in a position assumed when the door is closed, and with the night latch dead-locking mechanism in operative position. Fig. 4 is a plan view of the latch bolt. Fig. 5 is a view of the latch bolt

dead-locking lever detached. Fig. 6 is a view of one member of the night latch mechanism detached, and Fig. 7 is a view of the night latch dead-locking lever which is operated by the latch-bolt dead-locking lever. 60

In the embodiment of our invention herein selected for illustration, 1 indicates the lock case; 2 the face plate in which a spring latch bolt 3 is guided, the stem 4 of said bolt being provided with a spring 5 which normally projects the same and having at its rear end a cross head 6 arranged to cooperate with the usual cam arm of a cylinder lock mechanism or other suitable key-operated means, said cross-head also cooperating with a roll-back yoke 7 mounted upon the stems 8 and 9, said yoke being held by springs 10 and 11 on said stems in operative engagement with the outer roll-back 12 and the inner roll-back 13 (the latter being shown in dotted outline). The outer roll-back is provided with an extension 14, notched at 15 to receive the locking projection 16 of one member 17 of the night latch mechanism. Said member 17 is provided 80 with the usual push button 18 guided in the face plate 2 and is connected by lever 19 with the second member 20 of the night latch mechanism, the latter having a push button 21. The night latch mechanism is thrown 85 "on" by pushing in the member 17, whereby the locking projection 16 engages the outer roll-back 12 and is thrown "off" by pushing in the member 20, which through the lever 19 releases the member 17 from the roll-back. 90 Said mechanism may be held in the "on" or "off" position by any suitable form of spring.

The latch bolt is provided with the usual safety dead-locking means comprising the lever 22 pivoted at 23 on the lock case, said lever having an extension 24 adapted to be moved behind a shoulder 25 by a spring 26.

The lever 22 is normally held in inoperative position indicated in Fig. 1 when the door is open by the tail piece 27 of a controller 28 of well known form, which controller is retracted by the striker plate and held in retracted position when the door is closed whereby the tail piece 27 releases the lever 22 and permits the extension 24 thereof to engage behind the shoulder 25 of the latch bolt. The stem 8 of the roll-back yoke 7 is provided with a head 29 having a beveled face 30 adapted to lie beneath the in- 110

clined portion 31 of the lever 22, which, when the lever is in operative position, as shown in Fig. 3, serves to release the latch bolt when it is desired to operate the latter 5 by either the inner or outer knobs through their respective roll-backs. It is obvious however that when the outer roll-back is dead-locked by the night latch member 17, the latch bolt is effectually blocked against 10 operation by the outer knob.

To prevent tampering with the night latch mechanism when in operative position as described, we provide a dead-locking member 32 pivoted on the lock case at 33 and having 15 an arm 34 engaging a notch or slot 35 in an arm 36 of the lever 22. Said dead-locking member 32 also has an arm 37 adapted to engage in front of a shoulder 38 of a night latch member 17 when the latter is in operative 20 position as shown in Fig. 3. Hence, when the door is closed and the dead-locking lever 22 is in operative position, Fig. 3, the night latch mechanism when also in operative position is effectually blocked against 25 release when the door is closed.

While we have herein described a particular embodiment of our invention, it is obvious the same may be altered in detail and relative arrangement of parts within the 30 scope of the appended claims.

What we claim is:

1. In a lock, a latch bolt, a dead-locking lever therefor arranged to move into operative position upon closing the door, a roll-back 35 operable from the outer side of the door, deadlocking mechanism therefor and means separate from but operable by said dead-locking lever to block said roll-back dead-locking means against release when the 40 door is closed.

2. In a lock, a latch bolt, a dead-locking lever therefor adapted to move into operative position when the door is closed, a roll-back for said bolt normally operable from 45 the outer side of the door, dead-locking means for said roll-back and a separate lever operable by said dead-locking lever to block said roll-back dead-locking means against release when the door is closed.

50 3. In a lock, a latch-bolt, a dead-locking

lever therefor, a controller for said lever adapted to throw the same into inoperative position when the door is open and permit the same to move to operative position when the door is closed, a roll-back for said latch bolt operable from the outer side of the door, dead-locking means for said roll-back and a lever operable by said bolt dead-locking lever to block said roll-back dead-locking means against release when the door is 60 closed.

4. In a lock, a latch bolt, a dead-locking member therefor, a controller coöperating with said member and adapted to release the latter when the door is open and to permit the same to move to operative position when the door is closed, a roll-back for said latch bolt operable only from the outer side of the door, a dead-locking slide for said roll-back having means extending through 70 the face plate of the lock whereby the same may be moved to operative and inoperative position and means separate from but operable directly by said latch bolt dead-locking member to block said roll-back dead-locking means against release when the door is closed.

5. In a lock, a latch bolt, a dead-locking lever therefor, spring-actuated to operative position, a controller for said lever operated 80 by the striker plate to permit said lever to move to operative position when the door is closed, said controller being adapted to move said lever to inoperative position when the door is open, a roll-back for said latch bolt 85 operable only from the outer side of the door, a manually-operable dead-locking slide for said roll-back, a dead-locking member for said slide separate from but operable by said dead-locking lever adapted to be moved 90 to operative position to prevent release of said dead-locking slide when the door is closed by movement of said dead-locking lever to operative position with respect to said latch bolt.

AUGUST ARENS,
ERNEST L. TEIGH.
